UNITED STATES PATENT OFFICE.

ROBERT NEWTON LYONS AND WALTER EDWIN LYONS, OF WINNIPEG, MANITOBA,
CANADA.

BUILDING CONSTRUCTION.

1,414,293.

Specification of Letters Patent. Patented Apr. 25, 1922.

Application filed April 26, 1920. Serial No. 376,766.

To all whom it may concern:

Be it known that we, ROBERT NEWTON LYONS and WALTER EDWIN LYONS, both of the city of Winnipeg, in the Province of Manitoba, Canada, have invented certain new and useful Improvements in Building Construction, of which the following is the specification.

The invention relates to improvements in building construction, particularly to a double wall having an air space therebetween and the objects of the invention are to provide a wall having the various blocks thereof constructed from cement or such like composition and arranged so that the blocks can be all readily placed in position during the building operation and such that the completed double wall will be amply reinforced and will present from the exterior a regular appearance with the joints between the blocks in the various courses regularly alternating.

A further object of the invention is to provide a specially constructed tie block for effectively tying the inner and outer walls together and constructed to minimize the passage of moisture or frost from wall to wall.

A further object is to provide a wall formed from cement or such like blocks having proper provision therein for nailing the customary interior strapping.

With the above more important objects in view the invention consists essentially in the arrangement and construction of parts hereinafter more particularly described and later pointed out in the appended claims, reference being had to the accompanying drawing in which:

Fig. 1 is an exterior view of a portion of a wall constructed in accordance with our invention.

Fig. 2 is an interior view of the wall.

Fig. 3 is an enlarged detailed plan view of a portion of the wall.

Fig. 4 is an enlarged vertical sectional view through a portion of the wall.

Fig. 5 is a perspective view of one of the tie blocks.

Fig. 6 is a perspective view of one of the outer notched blocks.

Fig. 7 is a perspective view of one of the inner strapping blocks.

In the drawing like characters of reference indicate corresponding parts in the several figures.

The outer wall is formed from a plurality of similar cement or such like "course" or "regular" blocks 1 rectangular in cross section and of a predetermined length and a plurality of special "tie" blocks 2 rectangular in cross section and of the same length as the "course" blocks. In practice we make these blocks sixteen inches long, four inches wide and six inches high and when the wall is being built the various courses or layers are set so that the joints of the respective courses are staggered, thereby giving the outer wall a natural appearance as shown in Fig. 1.

The special "tie" blocks are inserted in selected courses or layers and in the present instance appear in every fourth course of the outer wall. The "tie" blocks are constructed as shown best in Fig. 5 where it will be observed they are of a T-shape presenting a block body or head 3 provided with a central extension or tie part 4.

The underside of the body part 3 is provided with the usual frog 5 whilst the extension is hollowed out from the underside to provide an air pocket 6. The body of the "tie" block is four inches wide and six inches high as is also the extension and the extension is five inches long, this giving a one inch air space between the walls as will be later apparent.

The various blocks forming the outer wall are set in mortar cement as is customary when the wall is being built, the frogs forming a bond between the successive courses.

The inner wall which is spaced one inch from the outer wall is made from a number of different types of blocks embodying what we choose to term "regular" course blocks 11, "special" course blocks 12, special "strapping" blocks 9 and special "notched" blocks 7, it being understood that the extensions of the tie blocks enter the inner wall at proper courses. The "strapping" blocks 9 (see Fig. 6) are of the same size as the "regular" blocks of the outer wall but they are notched

away centrally at the upper inner corner as indicated at 8. The "strapping" blocks are the same size as the notched blocks 7 with the exception that they have one end partially cut away as indicated at 10 to admit of the insertion in the wall of a wooden nailing strip.

The "regular" course blocks 11 of the inner wall are the same as the "course" blocks 1 of the outer wall whilst the "special" course blocks 12 are the same as the "regular" course blocks only they are twelve inches long.

The blocks forming the inner wall are built up in successive courses following in the order named:— "special" course blocks, "regular" course blocks, "strapping" blocks, "notched" blocks, and the various blocks are provided with the usual frogs for bonding purposes.

The two walls are built up at the same time and assuming initially that a layer of "tie" blocks is laid in the outer wall then a layer of "special" course blocks 12 is laid for the inner wall, these "special" course blocks 12 being placed between the extensions of the "tie" blocks.

Here it is to be observed that the total length of the "special" course blocks 12 plus the width of the extension equals sixteen inches which is the length of the "regular" course blocks of the outer wall.

The first layer of the inner and outer wall having been laid one can then build up three successive courses of the regular blocks of the outer wall, the joints being staggered as shown in Fig. 1.

In so far as the inner wall is concerned a course of "regular" blocks 11 is laid on the "special" blocks 12 with the joints between the ends of the "regular" blocks centered on the underlying "special" blocks. A course of "strapping" blocks is next laid on the "regular" blocks 11, the joints being staggered in respect to said "regular" blocks and after this is done a course of "notched" blocks 7 is laid, the notches being towards the air space between walls and taking a position immediately opposite the pockets 6 (see Fig. 4).

As the course of "strapping" blocks is laid short wooden strips 13 are inserted in the cut out corners 10 and bonded in the mortar cement, bonding the blocks. These strips 55 are exposed at the inner face of the inner

wall and provide a convenient means for 60 nailing the customary strapping to the inner wall to effect the interior finish of the wall.

The above completes the laying of four courses each of the inner and outer walls. This operation is repeated as the building 65 of the walls progresses, the "tie" blocks spacing the walls a fixed distance apart and tying them every fourth course, the wood strips 13 providing for the nailing of the strapping and the notches allowing of the 70 free entrance of air into the pockets which combined with the reduced cross sectional area of the extensions of the tie blocks, minimizes to a great extent the passage of moisture from the outer wall to the inner wall 75 by way of the extensions.

What we claim as our invention is:—

1. In a double wall construction having an air space between the walls, courses of tie blocks bonded in the outer wall and having 80 each tie block provided with a centrally positioned extension crossing the air space and entering the inner wall and a course of special blocks laid between the ends of the extensions and bonded in the inner wall. 85

2. In a double wall construction having an air space between the walls, courses of tie blocks bonded in the outer wall, the said tie blocks presenting heads bonded in the outer wall and extensions extending centrally from the heads and pocketed on the underside and with the extensions crossing the air space and bonded in the inner wall and the pockets communicating with the air space between the walls. 95

3. In a double wall construction, courses of tie blocks presenting heads bonded in the outer wall and extensions from the heads bonded in the inner wall and with the extensions cut away on the undersides to provide 100 air pockets and courses of notched blocks located in the inner wall and underlying the extensions and with the inner upper edges of the notched blocks cut away centrally and providing an enlarged entrance to the pocket 105 from the air space between walls.

Signed at Winnipeg, this 30th day of March, 1920.

ROBERT NEWTON LYONS.
WALTER EDWIN LYONS.

In the presence of—

GERALD S. ROXBURGH,
H. R. WAKEFIELD.
